UNITED STATES PATENT OFFICE

HENRY C. MAUL, OF DETROIT, MICHIGAN, ASSIGNOR TO DETROIT MICHIGAN STOVE COMPANY, OF DETROIT, MICHIGAN, A CORPORATION OF MICHIGAN

OVEN DOOR STOP

Application filed March 8, 1930. Serial No. 434,211.

This invention relates to pivotal supports and stops for doors and more particularly such devices for oven doors.

It has been the practice to provide supports for oven doors which shall be disposed within the door frame so as to eliminate protuberances caused by hinges, etc. formerly used. It has also become the custom to provide stops for the door, so that, when the latter is swung from its vertical or door closing position to its horizontal or door exposing position, the stop will operate to prevent the door from swinging below the desired horizontal shelf forming position.

It is an object of the present invention, therefore, to provide a device of the character above described, that is to say, a device which will form a combined pivotal and spring support and stop for the door.

It is a further object of the present invention to provide a device which can be enamored or plated on the side adjacent the door opening and which cooperates with the door or portions carried thereby in such a manner that danger of cracking or chipping the enamel is eliminated.

A still further object is to provide a combined pivotal support and door stop which is economical of manufacture, facile of application to the oven frame, and which is slightly in appearance.

Still further objects will readily occur to those skilled in the art upon reference to the following description and the accompanying drawings in which

Fig. 1 is a partial side view of an oven and door therefor, the device of the present invention being shown in dotted lines.

Fig. 2 is a side view of the pivot on the left hand side of the frame, the door being shown in its open position, and partially in section, the view being taken from the inside of the oven.

Fig. 3 is a side view of the left hand pivot taken from the outside of the oven, the outer portion of the frame being broken away and the door being shown in its closed position.

Fig. 4 is a back view of the same pivot taken from inside the oven, the door being shown as closed.

Referring to the drawings, there is shown in Fig. 1 an oven having a sheet metal body 10, a frame 11, a door 12 and a combined pivotal support and stop for the latter. The frame is substantially U-shaped in cross section, the base of the U being on the front of the oven and the sides of the U presenting surfaces which align with the sheet metal body and oven lining. The door, which is normally of the flush type, is pivotally supported in the frame at the lower portion of the latter, and when swung out to its horizontal or door exposing position, forms a shelf upon which a cooking utensil, when withdrawn from the oven, may be rested, if desired.

The pivotal support and stop of the present invention will now be described: The frame 11 is cut away on its inner side to form a notch 13, cooperating with the notch 14 in the stop 15 which is secured within the U frame by means of the bolts 16 threaded into a boss 17 of the frame thru the slotted aperture 18 in the stop. If desired, the bolt 16 may be a stud bolt, that is to say, a bolt wherein the nut portion is separate from the shank portion. The door 12 has trunnions 19 which enter the frame thru the perforations formed by pairs of cooperating notches 13 and 14, the door being pivotally swung with its trunnions in the perforations. On the back side of the stops 15 are inclined surfaces 21 which cooperate with horns or stop lugs 22 integral with and projecting from the trunnions 19 of the door. The stops 15 have portions 23 which extend in back of the lower edge of the door and which close such openings as might be otherwise left between the frame 11 and the sheet metal lining 24 of the oven.

When the door is in its vertical or closed position, as in Figs. 1, 3 and 4, the lugs 22 extend downwardly away from the frame at an angle of about 45 degrees, and when the door is swung downwardly to its horizontal position, the stop lugs rotate with the trunnions thru an angle of about 90 degrees, or until their upper surfaces engage the surfaces 21 of the stops 15.

If desired, I may provide means, such as a pin 25 on the stop lug 22 to which may be

secured a counterpoise spring 26 for the door.

It is the practice at present to enamel the exposed surfaces of the door and the door frame and it has also become the practice to 5 enamel similar surfaces on the pivotal supports and the stops, and stops as previously constructed were faulty in that the stop lugs carried by the door engaged enameled surfaces on the door stops. With the construction 10 of the present invention, the enameled surfaces of the door stops are not engaged by the stop lugs of the door, they engaging the stops only on the rear or unenameled surfaces thereof.

It will thus be observed that I have provided a construction which is particularly 15 adapted for oven doors and which is seen to have the advantages heretofore related.

Now having described the invention and 20 the preferred embodiment thereof, it is to be understood that the said invention is to be limited, not to the specific details herein set forth, but only by the scope of the claims which follow:

25 I claim:—

1. In combination, an oven frame, a door in front of said frame, and means to form a combined pivotal support and a stop for said door, said means comprising a member 30 disposed behind and secured to said frame and having a notched portion therein, a trunnion on said door adapted to ride in said notched portion, a lug carried by said trunnion at the end thereof and disposed behind said frame and a beveled stop surface on the rear wall of said member adapted to be engaged by the upper and forward surface of said lug when the latter is open.

2. In combination with an oven, a frame, 40 a perforation in said frame behind the forward surface thereof, a door adjacent and in front of said frame and having a trunnion disposed within said perforation, and a lug carried by said trunnion at the end thereof and adapted to abut the rear surface of said frame to form a stop for said door when the latter is open.

3. In combination with an oven, a frame, 50 a door adjacent said frame and opening forwardly thereof and having a trunnion, a stop member on the rear wall of said frame and having a trunnion supporting portion, and a stop lug carried by said door trunnion at the end thereof and adapted to abut the rear surface of the member to form a stop for said door when the latter is open.

4. In combination, an oven frame of channel cross section with the base of the channel forming the forward wall of the frame, a 60 door in and opening forwardly of said frame, and means at the lower part of said frame to form a combined pivotal support and stop for said door, said means comprising a member disposed in a notch in a side wall of the 65 channel of the frame and behind the forward

wall thereof and secured to said frame by a bolt threaded into the latter and thru the stop from the rear and having a forwardly opening notched portion therein, a trunnion on said door disposed in said notched 70 portion, a lug carried by said trunnion at the end thereof and disposed behind said frame, and a beveled stop surface behind the front wall of the frame, adapted to be engaged by the upper and forward surface of the lug 75 when the door is open.

5. In combination an over frame of U cross section with the base of the U forming the forward wall of the frame, a door in and opening forwardly of said frame, and means at the lower part of said frame to 80 form a combined pivotal support and stop for said door, said means comprising a member disposed in the U of the frame behind the forward wall thereof, and having a forwardly opening notched portion therein, a trunnion on said door disposed in said notched portion, a lug carried by said trunnion at the end thereof and disposed behind 85 said frame, and a stop surface on the rear wall of said member adapted to be engaged by the upper and forward surface of the lug when the door is open.
